[57] CLAIM

The ornamental design for a foot massager or the like,
as shown.

DESCRIPTION

FIG. 1 is a perspective view of a foot massager, or the like, showing my new design;

FIG. 2 is a front view thereof;

FIG. 3 is a right side view thereof; and

FIG. 4 is a top plan view thereof.

FIG. 5 is a central cross-sectional view of FIG. 2.
